UNITED STATES PATENT OFFICE.

CHARLES WILLIAM NICKLAUS, OF ELGIN, IOWA.

CAN-STRAIGHTENER.

SPECIFICATION forming part of Letters Patent No. 694,177, dated February 25, 1902.

Application filed December 24, 1901. Serial No. 87,084. (No model.)

To all whom it may concern:

Be it known that I, CHARLES WILLIAM NICKLAUS, of Elgin, in the county of Fayette and State of Iowa, have invented a new and useful Improvement in Can-Straighteners, of which the following is a specification.

The object of my invention is to provide a simple machine for taking the dents and kinks out of tin cans and otherwise straightening the cylindrical sides of the same when they have become dented or battered in any way; and it consists in the special construction and arrangement of a device for this purpose, which I will now proceed to describe with reference to the drawings, in which—

Figure 1 is a sectional side view; Fig. 2, an end view of the straightening-bed, and Fig. 3 a sectional detail showing a modification of the straightening-bed to adapt it to cans of different size.

In the drawings, A represents a metal bed-plate cast with a sleeve A', which is seated in any suitable support S. The bed-plate has formed on its upper front surface a cylindrical seat A² for the can.

Within the sleeve A' there slides a vertical stem B, which has a feather-and-groove connection a with the sleeve to keep the stem B from turning. On the upper end of the stem B there is detachably secured by a nut b a boss or hub B', having a former-arm B², whose lower surface is curved in cross-section to correspond to the curve of the concave bed. The bottom end of stem B is connected to a rod or bar C, which in turn at its lower end is loosely connected to a treadle D, fulcrumed at one end to the floor and bearing a foot-rest at the other end. This treadle is normally held up by a strong spiral spring E, whose upper end is hitched to an eye or hook on the bottom of the bed-plate A, and the action of this spring also holds the rod C, stem B, and former-arm B² in an elevated position, as shown by the dotted lines in Fig. 1.

To straighten the dents in cans, the can, which is shown at x, is laid upon the concave seat A², with the former-arm B² inside of the same, the dented portion of the can

being immediately beneath the former-arm 50 B². The foot is then applied to the treadle, and the former-arm B² is forcibly brought down against the wall of the can, compelling it to conform to the perfectly cylindrical curvature of the can-seat, and thereby pressing 55 out the dent.

To adapt my device to cans of different size, I may employ detachable can-seats A³, as seen in Fig. 3, which are secured to the bed-plate A by means of a bolt a', having a 60 countersunk head and a screw-threaded stem, that passes through the bed-plate and is tightened up by a nut on the lower side of the bed-plate. These detachable seats A³ are to be made with curvatures of different radius to 65 suit the different sizes of cans and are designed to be interchangeably used on the machine. In like manner the former-arm B² is made in series, with their lower surfaces adapted to the curves of different sizes of cans 70 and are interchangeably applied to the stem B.

Having thus described my invention, what I claim as new, and desire to secure by Letters Patent, is—

1. A can-straightening machine, consisting 75 of a bed-plate having a concave seat formed on its upper surface, a vertically-sliding stem passing through the bed-plate and having a feather-and-groove connection with the same, a former-arm connected to said stem above 80 the bed-plate and adapted to fit within the can-seat, and means for raising and lowering said former-arm substantially as described.

2. A can-straightening machine, consisting 85 of a bed-plate having a concave seat formed on its upper surface, a vertically-sliding stem passing through the bed-plate and having a feather-and-groove connection with the same, a former-arm connected to said stem above 90 the bed-plate and adapted to fit within the can-seat, a connecting-rod attached to the lower end of the former-arm stem, a treadle attached to the connecting-rod, and a spring connecting the treadle to the bed-plate substantially as shown and described. 95

3. A can-straightening machine, consisting of a bed-plate having a detachable concave seat, a vertically-sliding stem passing through

the bed-plate and having a feather-and-groove connection therewith, a former-arm detachably connected to said stem above the bed-plate and adapted to fit within the can-seat, 5 a connecting-rod attached to the lower end of the former-arm stem, a treadle attached to the connecting-rod, and a spring connecting the

treadle to the bed-plate substantially as and for the purpose described.

CHARLES WILLIAM NICKLAUS.
